Primary Examiner — April Rivas(74) *Attorney, Agent, or Firm* — Cantor Colburn LLP(57) **CLAIM**

I claim, the ornamental design for a trunk, as shown and described.

DESCRIPTION

FIG. 1 is a perspective view, taken from above, of a trunk showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, taken from below;

FIG. 9 is a perspective view, taken from above, of the trunk in another embodiment;

FIG. 10 is a front perspective view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a perspective view thereof, taken from below.

The broken lines illustrate portions of the trunk and form no part of the claimed design.
